THOMAS C. WILSON, OF FORT MILL, SOUTH CAROLINA, ASSIGNOR TO DRAPER CORPORATION, OF HOPEDALE, MASSACHUSETTS, A CORPORATION OF MAINE

THREAD CUTTING TEMPLE FOR LOOMS

Application filed June 5, 1931. Serial No. 542,351.

This invention relates to thread cutting temples for looms.

A principal object of my invention is to provide a thread cutter which shall be simple in construction and efficient in operation.

Further objects will be specifically pointed out hereinafter, and other objects will become apparent as the description proceeds.

In the drawings:

Fig. 1 is a plan view of a temple head embodying my invention.

Fig. 2 is a side elevation of the construction shown in Fig. 1, and

Fig. 3 is a view similar to Fig. 2, but showing parts of the head cut away to disclose the cutter mounted therein.

I have illustrated my invention in connection with a well known form of temple. This temple includes a temple bar 1 adapted to be yieldingly supported on a loom adjacent the selvage of the cloth. This bar supports a head 2 which includes a top 3 and a pod for housing the usual temple rolls (not shown). A guideway 4 is provided in the head for a cutter member 5. This cutter member consists of a rearwardly extending arm 6 having a depending cutter blade 7 at the rear end thereof, and a depending tail piece 8 at its front end. The cutter blade co-operates with a ledger blade 9 secured to the head.

While I have illustrated two cutter blades co-operating with a single ledger blade this structure may be changed as desired. The cutter member is provided with stops having angularly disposed faces 10 and 11 normally contacting similarly disposed faces 12 and 13 on the head.

A coil spring 14 has one end secured, as at 15, to the tail piece and the other end secured, as at 16, to the temple head. A supporting member 17 is provided having one end pivotally supported on a pin 18 on the head, and the other end pivoted on the pin 15 on the tail piece.

The operation of this cutter is as follows: The spring 14 and supporting member 17 normally retain faces 10 and 11 in contact with faces 12 and 13 respectively. As the lay beats up, the lay, or a suitable part pro-

vided thereon, strikes the tail piece 8 and causes the cutter member to pivot about point 19 until the cutter blade 7 is lowered to its lowest position. This movement hooks the blade about the filling. Continued movement of the lay will then cause the cutter member to slide longitudinally of the arm 6, thus drawing the blade 7 past its ledger blade and shearing the filling. As the lay recedes the spring 14 will return the cutter member to its initial position.

It has been proposed heretofore to provide similar cutter members with a spring somewhat similar in appearance to the present supporting member 17. This spring consisted of a torsion part supported on the pin 18 so that the arm corresponding to the depending arm of my supporting member acted as a spring.

This construction has not, in some cases, proven entirely satisfactory. As the eye at the lower end of the spring arm wore it allowed the cutter member to drop down; consequently, faces such as 11 and 13 were not in contact with each other, and operation of the tail piece by the lay would cause the end of the cutter member opposite the blade to rise until such faces came into contact with each other. This resulted in a slight change in the time of movement of the cutter blade downwardly. Also, with the old construction the resistance of the spring to sliding movement of the cutter member was sometimes insufficient to effectually cause the blade to rock about its pivot point before starting to slide. These two unintended changes in the timing of the rocking movement often resulted in failure of the cutter blade to hook behind the filling, with the result that the filling would not be cut.

It will readily be seen that with my construction the foregoing defects are effectually eliminated, for the supporting member 17 pivots freely about the pins to which it is attached and is not subject to such rapid wear, and the arrangement of the spring is such as to always cause the cutter blade to drop down behind the filling before starting to withdraw.

I claim as my invention:

1. A loom temple including a temple bar; a temple head supported by said bar; a rockable and slideable cutter member supported in a guideway in said head, said cutter member including a rearwardly extending arm having a depending cutter blade at one end thereof and a depending tail piece at the other end thereof; a coil spring having one end secured to said tail piece and the other end secured to said head so as to extend diagonally of said arm and said tail piece, and a supplemental supporting member for the extreme forward end of said arm.
- 15 2. A loom temple including a temple bar; a temple head supported by said bar; a rockable and slideable cutter member supported in a guideway in said head and including a rearwardly extending arm having a depending cutter blade at one end thereof and a depending tail piece at the other end thereof, said arm sliding in said guideway; stops on said cutter member having angularly related faces adapted to contact corresponding faces on said head; a coil spring having one end secured to said tail piece and the other end secured to said head so as to extend diagonally of said arm and said tail piece; and a supporting member for said cutter member, having one end pivoted to said tail piece and the other end pivoted to said head, whereby faces of both said stops are yieldingly maintained in contact with the said faces on said head.

THOMAS C. WILSON.
